IRONER CONTROL MECHANISM

Merlin S. Vincent, Newton, Iowa, assignor to
Automatic Washer Company, Newton, Iowa,
a corporation of Delaware

Application October 13, 1937, Serial No. 168,710

4 Claims. (Cl. 74—515)

This invention pertains to control mechanisms for controlling the operation of an ironing machine or the like and, more particularly, to a control mechanism which may be used for starting and stopping the ironer roll and moving the ironing shoe into and out of ironing engagement with the roll.

The primary object of the invention is to provide a control mechanism of such character that the machine operator may operate the control with either of her knees, the device being so constructed and arranged that the portion of the control which is engaged by the operator's knee may be quickly adjusted to accommodate operation by either knee, the control also being of such nature and construction that movement of an operating arm or knee engagement portion in either of opposite directions will effect the control.

Other objects as well as the advantages and uses of the invention will be or should become apparent and understood after reading the following description and claims and after viewing the drawing in which:

Fig. 1 is a fragmentary front elevation of the upper portion of the ironing machine including a portion of the roll and the driving head thereof, showing a preferred form of my invention applied thereto;

Fig. 2 is a view partly in section and partly in elevation of the right hand end of the mechanism shown in Fig. 1; and

Figs. 3, 4 and 5 are detail views illustrating three positions of a rocking member utilized in the control, the positions shown in Figs. 3 and 5 being operated positions and the position in Fig. 4 being a normal position.

The ironing table or cabinet is represented only by the top portion 2 which supports a casting 3 which houses the power mechanism for driving the ironing roll 4 and operating the ironing shoe (not shown) and which also houses certain control mechanisms whereby the operation of the roll and the operation of the ironing shoe may be controlled. In the present instance the mechanism embodying the invention is illustrated as utilized for the control of a device which may move the ironing shoe toward and from the roll and which may also be used to start and stop the roll itself.

As illustrated, a control member 5 mounted upon a shaft (not shown) for rotation therewith in the direction of the dotted line arrow shown in Fig. 2, has a pair of lugs 6 either of which

5 may be engaged by a hooked stop 7 forming one arm of a bell crank lever 8 which may be fixed upon a pivoted pin 9 mounted within the housing 3. The hook 7 of the bell crank lever 8 is adapted to be moved momentarily from the full line to the dotted line position shown in Fig. 1 to permit the escapement of one of the lugs 6, the hook 7 being permitted to return immediately to its initial position whereby to engage the succeeding lug 6 as the same rotates around through an arc of 180°. Mechanism of this sort is well understood in the art.

The arm 11 of bell crank lever 8 is pivotally connected with what may be termed a pull rod 12, the arm 11 having an elongated slot 13 for the passage of the bent end of the rod 12 which may be held therein and therethrough by a pin 14 as will be understood. The lower end of the pull rod 12 is rigidly secured to a yoke 15 each of the arms 16 of which are slotted as shown at 17 for the reception of a pin 18 therein and therethrough. The pins 18 are secured to opposite sides at one end of a member 19 which is pivotally supported in a bracket 21 secured in any suitable manner to the frame 2. The other end of member 19 is secured to a crank arm 22 which in turn is pivotally connected to what may be termed a push-pull rod 23 which may be slidably supported for movements in either direction longitudinally of its axis in one or more brackets 24 suitably secured to the frame 2. It will be apparent from the foregoing that if the push-pull rod 23 is moved to the right, viewing Figs. 1 and 5, the crank 22 will be rocked to the right which will depress the right hand pin 18 and raise the left hand pin 18. Since the pivot axis 25 of member 19 is fixed, and since the pins 18 normally rest as shown in Fig. 4 at the bottoms of the slots 17, the rocking movement of the crank 22 will cause a downward pull upon the rod 12, which in turn will swing the bell crank lever 8 about its pivot in a counter-clockwise direction thereby to release one of the lugs 6. Likewise, if the push-pull rod 23 be moved to the left viewing Fig. 1, the left hand pin 18 will similarly move the rod 12 downwardly and perform the same operation.

In order to move the push-pull rod 23 to the right or to the left, it is provided with a handle 25 which is located in the path of movement of an operator's knee and depending upon the desire of the operator may be operated by a nudge or a sidewise motion of either knee. In order that the handle may be disposed where most satisfactory for operation by the operator's knee, it is secured to a block 26 adapted to slide freely

upon the push-pull rod 23 and with a pair of spring arms 27 each of which is provided with an aperture through which the push pull rod 23 may slide freely when the depending ends of the arms 27 are pinched toward one another but which will bind against the marginal portions of the apertures when the depending portions of the arms 27 are released. The construction is very similar to the common transom rod stop. By manipulating the spring arms 27 an operator may dispose the handle 25 in its most convenient position for use and where the handle may be operated by either knee and the control operated by moving the handle in either direction.

15 It is believed that the construction and operation will be fully understood from the foregoing and that further description thereof is unnecessary. It is to be noted, however, that while I have illustrated and described the preferred form of 20 the invention, the same is susceptible of various other forms and of various modifications and may be applied for other uses. Consequently, I do not desire to be limited except by the spirit of the invention and the scope of the appended 25 claims.

I claim:

1. In a control mechanism of the character described having a releasable member adapted normally to engage another member for retaining 30 the latter in predetermined position, said releasable member being movable between a released and an engaging position with respect to said other member, means for operating said releasable member comprising, a pull rod, a forked member secured to said rod, said forked member having closed slots in its arms, a rockable member mounted upon a fixed pivot between said arms and having portions disposed in and movable between the ends of said slots, a crank secured relative to said rockable member, and 35 means including a push-pull rod connected with said crank for rocking said rockable member.
2. In a control mechanism of the character described having a releasable member adapted normally to engage another member for retaining 40

the latter in predetermined position, said releasable member being movable between a released and an engaging position with respect to said other member, means for operating said releasable member comprising, a pull rod, a forked member secured to said rod, said forked member having closed slots in its arms, a rockable member mounted upon a fixed pivot between said arms and having portions disposed in and movable between the ends of said slots, a crank secured relative to said rockable member, a push-pull rod connected with said crank for rocking said rockable member, a handle, and an infinitely variable spring clamp for securing said handle to said push-pull rod.

15 3. In a control mechanism of the character described, a releasable member adapted to normally engage a clutch member to hold it in inoperative position, said releasable member being pivotally movable to disengage the clutch member 20 into operating position, manual means for operating said releasable member comprising a forked pull rod, closed slots in said forks, a bell crank engaging the ends of said slots on one end, a push-pull rod engaging the opposite end of the bell crank, and a vertical handle adjustably attached to said push-pull rod, said handle being adjustably held by a dual-armed clamp spring releasable by pinching the arms together.

25 4. In a control mechanism of the character described, a releasable member adapted to normally engage a clutch member to hold it in inoperative position, said releasable member being pivotally movable to disengage the clutch member 30 into operating position, manual means for operating said releasable member comprising a vertical pull rod, a bell crank pivotally connected to said pull rod on one end, a horizontal push-pull rod attached to the opposite end of said bell 35 crank, and a vertical handle adjustably attached to said push-pull rod, said handle being adjustably held by a dual-armed clamp spring releasable by pinching the arms together.

MERLIN S. VINCENT.
